Inventor.

Albert H. Pierce

UNITED STATES PATENT OFFICE.

ALBERT H. PIERCE, OF HILSDALE, MICHIGAN.

DEVICE FOR LOCATING SUNKEN BOATS.

SPECIFICATION forming part of Letters Patent No. 579,548, dated March 23, 1897.

Application filed June 25, 1895. Serial No. 554,052. (No model.)

To all whom it may concern:

Be it known that I, ALBERT H. PIERCE, a citizen of the United States, residing at Hillsdale, county of Hillsdale, and State of Michigan, have invented a new and useful Device for Locating Sunken Boats or Vessels and for Raising or Recovering the Same or Portions Thereof, a description of which is fully set forth in the following specification.

10 The object of my invention is to make a device for locating sunken boats and recovering the same or things thereon that shall be both easy of construction and certain in operation.

15 Figure 1 is a view of my device on a boat that has gone to the bottom. Fig. 2 is a view of the cone-shaped eye. Fig. 3 is a view of the grappling clamp and ring. Fig. 4 in the upper part is a view of the grappling-clamp as 20 being run down the cable. In the lower part, dotted lines, is a view of the grappling clamp and ring in place on the cone-shaped eye.

25 For the purpose of locating the place of the sunken boat or vessel the signal, which may be the buoy A or balloon A', Fig. 1, is used. The buoy is made in any desired form and size and of such material as will cause it to rise and float on the surface of the water if the boat or vessel should sink. If a balloon 30 is used, it is made in any desired form and size and of such material and inflated with such substance as will cause it to rise above the surface of the water in case the boat or vessel should sink.

35 The rope B, Fig. 1, is used to connect the buoy A or balloon A' with the boat or vessel, and serves also another purpose, as will appear farther on.

40 The cone-shaped eye C, as shown in Figs. 1, 2, and 4, is made as follows: The cone has an orifice through it, through which the rope B is to pass from the reel E, Fig. 1. The base of the cone is concave, and from the center of the base of the cone a stem projects, which 45 is fastened to the boat or vessel or anything thereon that is to be recovered. In this stem projecting from the base of the cone is a ball-and-socket joint I, as shown in Figs. 1, 2, and 4, to admit of its being adjusted to a vertical

position. The grappling-clamp F, as shown 50 in Figs. 3 and 4, is made cone-shaped, of two pivotally-connected jaws convex on the outside and concave on the inside, fastened together at the top or apex and with a heavy flange on the inside at the base, and a heavy 55 cable of any desired length and strength is also fastened at the top or apex. The ring G, as shown in Fig. 3 and in dotted lines in Fig. 4, is made to fit over the jaws of the grappling-clamp F and hold them firmly in place. 60

Having described the construction of the different parts of my device, I will now describe the operation.

65 The cone-shaped eye C, Fig. 1, is fastened to the boat or vessel or anything thereon that is to be recovered. The free end of the rope on the reel E is then threaded up through the cone-shaped eye C and fastened to the buoy A or balloon A', which are so placed as to readily rise to the surface if the boat or vessel should sink. This forms the signal part 70 of my device for locating the place of the sunken boat or vessel and is shown in Fig. 1. For recovering the boat or vessel or thing to which the cone-shaped eye C is fastened 75 the signal is taken from the rope B and the grappling-clamp F is threaded onto it and run down over the cone-shaped eye C, the flange at the base of the jaws of the clamp F clasping over the base of the cone-shaped eye 80 C. The ring G is then threaded onto the rope B and the cable H and run down onto the jaws of the grappling-clamp F, which holds them firmly in place and is shown by dotted lines in Fig. 4. 85

Having described the construction of the different parts of my invention and their operation, what I desire to secure by Letters Patent is—

90 In an apparatus for locating or recovering sunken boats, the combination of the shoulder-shaped eye C having an orifice through it, said cone-shaped eye being fastened to the boat, the rope B, passed up through said orifice, a signal attached to said 95 rope and adapted to rise to or above the surface of the water, a grappling-clamp F having two pivotally-connected jaws each hav-

ing a heavy flange on the inside of its base, said clamp being adapted to be run down on the rope and engage the shoulder of the cone-shaped eye, the ring G also being adapted to be run down on the ropes B and H and onto the grapping-clamp to hold the jaws of the clamp firmly in place, and the cable H at-

tached to the ring at the top of the grapping-clamp, substantially as described.

ALBERT H. PIERCE.
